(57) **CLAIM**

The ornamental design for a baby basket, as shown and described.

DESCRIPTION

FIG. 1 is a perspective view of a baby basket showing our new design;

FIG. 2 is a right side view thereof;

FIG. 3 is a top plan view thereof;

FIG. 4 is a front perspective view thereof;

FIG. 5 is a rear perspective view thereof; and,

FIG. 6 is a left side view thereof.

The broken lines shown in the drawings depict portions of the baby basket and form no part of the claimed design.

1 Claim, 6 Drawing Sheets
